UNITED STATES PATENT OFFICE.

JOHN H. BALDWIN, OF SPRINGFIELD, MISSOURI.

HAND-TOOL.

1,119,791.

Specification of Letters Patent.

Patented Dec. 8, 1914.

Application filed November 24, 1913. Serial No. 802,841.

To all whom it may concern:

Be it known that I, JOHN H. BALDWIN, a citizen of the United States, residing at Springfield, in the county of Greene and 5 State of Missouri, have invented certain new and useful Improvements in Hand-Tools, of which the following is a specification.

This invention relates to improvements in hand tools, and particularly to a single appliance adapted for use either as a wrench 10 or as wire cutters and pliers or tongs.

My object is to produce a convenient tool of this character having jaws, in which provision is made for readily adjusting the jaws 15 when the tool is used as a wrench, for any size intermediate the maximum and minimum sizes for which the tool is adapted without movement of the handles, which may be closed together or spaced apart as 20 desired. The improved construction also enables one of the handles of the tool, when used as pliers, to be adjusted to dispose the handles at the proper distance apart to permit the workman to manipulate and hold 25 them to the best advantage.

With these objects in view, my invention comprises various novel and peculiar details of construction and organization, all as hereinafter described and particularly 30 pointed out in the appended claims; and to afford a full and complete understanding thereof, reference will be had to the accompanying drawing, in which—

Figure 1, is a plan view of the tool showing it in closed position, and also illustrating in dotted lines the adjustable jaw in a different position of adjustment. Figs. 2, 3, and 4 are perspective views of certain 35 portions of the device, and Fig. 5, is a detail plan view, partly in section, and broken away, of the handle member which carries the adjustable jaw.

Referring to the drawing, 2 indicates one of the handles provided with a fixed jaw, 45 4, *i. e.*, fixed with relation to the handle carrying it. The other handle 6 carries the adjustable jaw 8, the handles and jaws being both of said jaws having both flat and ribbed portions as shown, to adapt them to be 50 used either as a wrench or as pliers. The pivot head 10 of the handle 2 is about one-half as thick as the handle and is flush at its outer side therewith, and at its inner side is equipped with a recess 12 receiving 55 and providing angular play for the pivot

lug 14 of the handle 6. A companion recess 16 for accommodating this pivot lug is also formed in the inner face of the pivot head 18 of the adjustable jaw 8, which head 18 is about one-half as thick as its jaw and flush 60 at its outer side therewith so that the two heads when fitted together correspond in thickness with the jaws and handles. A rivet 20, or equivalent means, is employed for securing the parts together in pivotal 65 relation, said rivet passing through the openings 22, 24, and 26 provided in the parts 10, 14 and 18 respectively.

At the base of the pivot lug, the handle 6 is provided with a pair of lugs 26^a and 28, 70 forming between them a socket in which to mount a worm 30, having a suitable bore for journaling the same upon a pin 32 passed through said lugs, said pin being threadedly engaged with the lug 28 and having its head 75 countersunk in the lug 26^a. The worm 30 is so positioned as to engage a series of teeth 34 provided on the rear edge of the pivot head 18, the teeth being arranged in a circle about the axis of the rivet 20 as a center. 80 The thread of the worm is suitably knurled, as shown in Fig. 1, to facilitate the manipulation thereof by hand.

From the foregoing it will be apparent that by proper manipulation of the worm 85 30, the jaw 8 may be readily adjusted, in order to adjust the tool as a wrench to any desired size intermediate the largest and smallest sizes for which the tool is adapted,—as illustrated for example by the dotted 90 lines in Fig. 1. By this means, the tool is given a largely varied capacity, as well as great facility of operation. Besides affording this ease of adjustment to different sizes as a wrench, the same advantages apply to 95 its use as pliers, since it is readily seen that the handles may quickly be closed together or located the desired distance apart so that the workman may operate them to the best advantage. 100

The usual recesses 36 are provided in the heads 10 and 18 adjacent the base of each jaw, for the purpose of cutting wire. I further provide means for definitely limiting the maximum spread of the jaws, which 105 means comprises forwardly facing shoulders 38 and 40 formed on the head 10 and designed to engage respectively with rearwardly facing shoulders 42 and 44 formed on the head 18 of the movable jaw. This 110

affords a strong construction whereby the jaw 8 is shouldered for its entire width, half of it, at shoulder 42 bearing directly on shoulder 38 while the other half at 5 shoulder 44 bears against shoulder 40, the jaw 8 is therefore definitely and firmly supported against any further movement when used in wide-open position as a wrench.

While I have illustrated and described 10 what I now believe to be the preferred form of the invention, I reserve the right to such modifications and variations thereof as may fairly fall within the scope of the appended claims.

15 I claim:

1. In a tool, the combination with a jaw, a head and a handle in fixed relation, the head being of less thickness than the handle and jaw, and the handle having a laterally-offset front end at one side of the head providing a forwardly-facing shoulder, and the head having a similarly facing shoulder between the handle shoulder and the rear end of the jaw and at the same side of the center of the head as the handle shoulder; of 20 a second jaw and head, the latter fitting flatly against the first-named head and being pivoted thereto, said second head having a peripheral rearwardly-facing shoulder to abut against the forwardly facing shoulder of the handle, and the second jaw having a rearwardly-facing shoulder to abut against the forwardly facing shoulder of the head, the two sets of shoulders 25 jointly providing stops for the full width of the tool whereby to limit the separating adjustments of the jaws.

2. In a tool, the combination with a jaw, a head and a handle in fixed relation, the 40 head being of less thickness than the handle and jaw and the handle having a laterally-offset front end at one side of the head providing a forwardly-facing shoulder, and the head having a similarly facing shoulder between the handle shoulder and the rear end of the jaw and at the same side of the center of the head as the handle shoulder; of 45 a second jaw and head, the latter fitting flatly against the first-named head and being pivoted thereto, said second head having a peripheral rearwardly-facing shoulder to abut against the forwardly facing shoulder of the handle, and the second jaw having a rearwardly-facing shoulder to abut 50 against the forwardly facing shoulder of the head, the two sets of shoulders jointly providing stops for the full width of the tool whereby to limit the separating adjustments of the jaws, a handle pivoted 55 to said head, and means carried by said second handle for locking the same in rigid relation to the said second head, so that pivotal movement of said handle shall be accompanied by like movement of said head, 60 said means being independently movable to 65

rotate said head and cause its jaw to move toward or from the first-named jaw independently of movement of the handle.

3. In a tool the combination with a jaw, a head and a handle in fixed relation, the 70 head being of less thickness than the handle and jaw and the handle having a laterally offset front end at one side of the head providing a forwardly facing shoulder and the head having a similarly facing shoulder between the handle shoulder and the rear end of the jaw and at the same side of the center of the head as the handle shoulder; of a second jaw and head, the latter fitting flatly against the first-named head and being pivoted thereto, said second head having a peripheral rearwardly-facing shoulder to abut 80 against the forwardly facing shoulder of the head, the two sets of shoulders jointly providing stops for the full width of the tool whereby to limit the separating 85 adjustments of the jaws, a handle pivoted to 90 said head, said second head having peripheral teeth, and a worm carried rotatably by said second handle and meshing with the teeth of said head.

4. In a combination wrench and pliers, 95 the combination of a pair of handles pivoted together, a jaw carried by each of said handles, one of said jaws being adjustable angularly with reference to its handle, said adjustable jaw having a pivot head provided 100 with a series of teeth arranged concentric with the pivotal axis of said adjustable jaw, a pair of lugs carried by the last-mentioned handle adjacent its pivot, a pin mounted in said lugs, and a worm journaled on said pin 105 in mesh with said teeth for adjusting said adjustable jaw.

5. In a tool, the combination with a circular head having at opposite points a forwardly projecting jaw and a rearwardly 110 projecting handle, the said head and other parts being flush at their outer sides, and said head being about half the thickness of said jaw and handle; a second circular head fitting flatly against the first and provided with a forwardly projecting jaw of the same dimensions as the first-named jaw, the said head being about half the thickness of its 115 jaw and at its outer side flush with the outer side of the latter; a second handle having a 120 forwardly projecting lug fitting between said heads, a pivot connecting the heads and said lug together, parallel lugs projecting laterally from the lug-carrying handle, and a worm carried by and arranged between 125 said parallel lugs, the said second jaw having peripheral teeth meshing with said worm and pivotally movable through movement of the handles or through rotation of said worm.

6. A tool comprising a handle having a rigid jaw at its front extremity, a handle having a lug at its front extremity overlapping the first-named handle, a pivot extending through the first-named handle and the lug of the other handle, a second jaw mounted on the same pivot as the handles, and coöperatively disposed with reference to the first jaw, and provided with teeth extending concentrically of said pivot and arranged at the opposite side of the same from the jaws, and a worm carried by the han-

dle provided with the lug and intermeshing with the said teeth and adapted when its carrying handle is moved to pivotally operate the second jaw and when rotated around its own axis to impart pivotal action to said jaw independent of said carrying handle. 15

In testimony whereof, I affix my signature, in the presence of two witnesses.

JOHN H. BALDWIN.
